SECTIONAL INSULATED FLOOR

Albert Dietrich, New York, N. Y., assignor to the
United States of America as represented by the
Secretary of the Army

Application July 14, 1950, Serial No. 173,735

1 Claim. (Cl. 20—6)

1

My invention relates to sectional floors and more particularly to such floors as incorporate heat insulation therein whereby the transmission of heat or cold through the floor is materially retarded.

The floor according to the invention is particularly adapted for buildings of either a permanent or temporary nature particularly the latter which are erected in cold regions such as the Arctic and Antarctic regions. In such regions, the cold is extreme and outdoor work even with adequate clothing is hazardous except for extremely short periods of time. Also, the ground is always frozen to substantially great depths and/or covered with frozen snow or ice whereby the leveling of an area suitable for the foundation of the building is not only extremely difficult but requires a relatively large number of outdoor working periods which are, as aforesaid, undesirable.

Consequently, it is highly desirable to provide a floor which will be capable of being seated directly on the ground and/or the frozen covering thereof with little or no grading, which will have adequate insulating qualities and yet which will be self leveling to a great extent whereby at least the smaller surface irregularities are impotent to distort the floor or portions thereof out of the general level of the terrain. Obviously, to facilitate portability, such a floor must be formed of a plurality of portable sections or panels and there must be provided means for connecting the several panels together which are simple in operation and which may be actuated by personnel wearing gloves. Finally, at least certain of the panels should include sill-providing means or the like to facilitate the attaching of the building studs and/or walls thereto.

With the foregoing in view, it is an object of my invention to provide an improved sectional, insulated floor.

A further object is to provide an improved sectional floor which includes a bottom, foundation-providing lamination of insulating material.

A further object is to provide a floor such as that last described, wherein the insulating material is composed of resilient material and of sufficient thickness to envelop at least the smaller surface irregularities whereby to render the floor self leveling.

A further object is to provide a floor such as that last described which is composed of a plurality of interfitting panels, together with means for readily detachably connecting said panels together in edge-to-edge relation.

A further object is to provide in such a floor,

2

opposed marginal rows of sill panels bounding opposite sides of a main body of floor panels, such sill panels having sill-providing means on the upper surfaces thereof.

5 A further object is to provide such a floor wherein the assemblies of sill panels have joints in offset relation to the joints of the assembly of floor panels whereby to increase the rigidity of the entire floor.

10 Other objects and advantages reside in the particular structure of my invention, in the structure of the several elements thereof, combinations, subcombinations and arrangements of such elements, all of which will be readily apparent to those skilled in the art upon reference to the attached drawing in connection with the following specification wherein the invention is shown, described and claimed.

In the drawing:

20 Figure 1 is a plan view showing one form of floor according to the invention;

Figure 2 is a plan view on an enlarged scale of one of the sill panels of the floor;

25 Figure 3 is an enlarged, fragmentary perspective view of the upper left hand corner of Figure 1 showing a building wall attached to the floor;

Figure 4 is an enlarged, transverse vertical sectional view taken substantially on the plane of the line 4—4 of Figure 3;

30 Figure 5 is a fragmentary plan view of a slightly modified floor.

Referring specifically to the drawing, wherein like reference characters have been used throughout the several views to designate like parts, 10 designates generally one form of floor according to the invention which may provide a foundation for any suitable building which is generally designated by 11. In the embodiment illustrated, the building 11, is made according to the building more specifically disclosed in my copending application filed June 19, 1950, Serial Number 169,022; now Patent No. 2,647,475; but obviously the floor is applicable to other forms and types of buildings.

The floor 10 of Figure 1 comprises a rectangular assembly of like floor panels 12 which, in the form illustrated, is bounded on at least two opposite sides by elongated assemblies of rectangular sill panels 13. It is desirable to have a definite relation between the length and width of the sill panels 13 and length and width of the floor panels 12 so as to permit not only enlarging and reducing the size of the floor by adding or subtracting sill and floor panels but also to permit

the formation of a rectangular floor. Thus, in the embodiments illustrated, each sill panel 13 is as long as the combined width of two floor panels and equally as long as each floor panel. Also the sill panels 13 are one half as wide as the floor panels 12. These proportions, or others to the same effect, permit the formation of the rectangular floor 10' of Figure 5. The floor 10' is formed by allowing the terminal sill panels 13 of each sill panel assembly to project beyond the ends of the floor panel assembly. The spaces between the projecting ends of sill panel assemblies are filled in by slightly modified sill panels 13', providing end sill panel assemblies, whereby a rectangular floor may be formed if desired.

It should be noted that the side sill panel assemblies are offset relative to the floor panel assembly so that the transverse joints between adjacent sill panels 13 are out of registry with the corresponding joints between adjacent floor panels 12. Likewise, in Figure 5 by making the sill panels 13' one and one half times longer than the floor panels 12, the joints between end sill panels 13' are out of registry with the longitudinal joints between the floor panels 12. The effect of this arrangement is important in that it gives longitudinal rigidity to the floor 10' of Figure 1 and longitudinal and transverse rigidity or all around rigidity to the floor of Figure 5 whereby to strengthen the same.

Each floor panel 12 and sill panel 13 or 13' is of a laminated nature to provide a relatively rigid floor-providing lamination 17 at the top and a resilient or yielding foundation providing lamination 18 of insulating material at the bottom. The floor-providing laminations 17 may be of any suitable material and structure and their actual makeup forms no part of the present invention. Lightness, strength and heat insulating qualities are desirable and a number of commercial panels are suitable for my purpose. For instance, each of the floor providing laminations 17 may comprise top and bottom skins 14 of metal covering a honeycomb body 15 of any suitable material. The bodies 15 are preferably bounded by frames 16 of wood or other suitable rigid material.

The floor-providing laminations 17 are bonded in any suitable manner to relatively thicker foundation-providing laminations 18 each of which is composed of resilient insulating material preferably of the nature of sponge rubber. Sponge rubber is suitable for most climates but where it is to be expected that temperatures below the freezing point of rubber are to be encountered, synthetic equivalents of sponge rubber having sufficiently low freezing points should be substituted. Indeed, sponge rubber-like material may be eliminated entirely from the foundation-providing laminations and non-freezing yieldable insulated material of any suitable nature substituted if desired.

The floor panels 12 and sill panels 13 interfit by means of tongues 19 formed on two adjacent edges of the frames 16 of each floor-providing lamination 17 of each panel and complementary grooves 20 formed in the remaining edges of such frames 16. The panels of each assembly are locked together and the sill and floor panel assemblies are locked to each other by any suitable fasteners of a type which may be operated by gloved personnel. Thus, for example, the upper edge portions of each floor panel 12 may be formed with a semi-circular recess 21, Fig. 3, on each side of and adjacent to each corner thereof. Such recesses 21 each have secured therein a

semi-detent means 22. When the panels are assembled, each recess 21 will register with a complementary recess 21 and semi-detent means 22 of an adjacent floor panel. Likewise, identical recesses 21 and semi-detent means 22 are located on the sill panels 13 so as to register with complementary recesses and detents of adjacent floor and sill panels. A single rotary cam fastener 23 may now be inserted into each pair of registered recesses 21 for operative engagement with the pairs of semi-detents 22 therein. Rotation of the fasteners 23 clamp the adjacent panels together in a well known manner. The fasteners 23 may be protected against damage by caps 24 which are held in place in any suitable manner as by spring fingers 25 depending therefrom which engage beneath flanges 26 on the fasteners which engage beneath flanges 26 on the fasteners 23. The particular fastener illustrated is a well known commercial item which is disclosed in Patent Number 1,584,069 to Anderson, dated May 11, 1926, and forms no part of the present invention except in combination with the rest of the structure.

It should be noted that the foundation-providing laminations 18 are slightly laterally offset relative to the floor-providing lamination 17, as best seen in Fig. 4. It is understood, also, that the laminations 17 and 18 are similarly longitudinally offset. This arrangement offsets the joints 20 between abutting laminations 18 relative to corresponding joints between laminations 17.

The sill panels 13 are best seen in Figures 2, 3 and 4 and as each is identical it will suffice to describe but a single one of them. A pair of sills 35 or sill boxes 27 is mounted atop each sill panel 13 in spaced longitudinal alignment by any suitable fastening means such as the bolts 28 which pass downwardly therethrough, Fig. 4, and through the floor-providing lamination 17. Spacer blocks 32 between the metal skins 14 are bored for the passage of the bolts 28 and relieve the honeycomb structure 15 from crushing strains as the nuts 33 of the bolts 28 are tightened to clamp the sill boxes 27 in place. Likewise, Figure 2, the honeycomb structure 15 is relieved of crushing strains 45 of the walls 35 by means of cross braces 34, two or more of which are disposed below each sill box 27 between the skins 14 of the sill panels 13.

Each sill box 27 may be of hollow tubular structure and for the form of building disclosed here and in my co-pending application aforesaid, will have upwardly converging side walls 29 each of which is formed with a row of bolt holes 30. Nuts or like fasteners 31 are welded or otherwise secured to the inside of each side wall 29 in axial alignment with the bolt holes 30. Thus, bolts 36 may be passed through the walls 35 of the building and the bolt holes 30 for threaded engagement with the nuts 31 whereby the walls are anchored to the sill boxes 27. Obviously, if the building involved has vertical walls, the side walls 29 of the sill boxes 27 would likewise be vertical.

Each sill panel 13 is provided with a plurality of spacer blocks 37 between the skins 14 and on opposite sides of the sill boxes 27. Such spacer blocks are formed with downwardly and angularly directed holes which are continued through the skins 14 and which are preferably lined with any suitable bushings 38. Any suitable anchor stakes 39 may be driven through the bushings 38 and aligned holes 40 in the foundation-providing laminations 18 so as to seat in the ground and anchor the floor 10 thereto.

The end sill panels 13' may be identical to the 75 sill panels 13 but have been here modified slightly

in size, position of sill boxes 27' and position of the recesses 21' to suit specific needs involved. However, otherwise they are identical to the sill panels 13 so a detailed description thereof is believed to be unnecessary.

It will be apparent from the foregoing that the floor 10 may be readily set up on reasonably level ground without regard to at least minor surface irregularities as these will be enveloped by the foundation-providing laminations as shown in Figure 4. Thus, little or no grading is required prior to the setting up of the floor. Inasmuch as the side edges of the foundation laminations 18 are in resilient abutting relation with the adjacent laminations 18, substantially draft free joints are formed. This feature, together with the inherent insulating properties of the laminations 18 and the offsetting of the joints of the laminations as aforesaid, provide a substantially airtight floor with excellent heat insulating properties whereby the floor 10 may be laid directly on snow, ice or frozen ground. Likewise, the insulating properties of the floor are useful in retarding the transmission of heat from the interior of the building which, for obvious reasons, is highly desirable when the building is erected directly on frozen snow or ice.

It follows from the foregoing that I have provided a combined floor, foundation and sill structure which is inherently light in weight and yet which is sufficiently strong for its purpose. Moreover, the floor 10 may be readily laid by unskilled personnel wearing gloves with a minimum of effort and without special tools. Obviously, the nature of the connections between the panels is such that a floor of any desired size or shape may be readily laid merely by adding or subtracting appropriate numbers of floor and sill panels. Likewise, the structure of the several panels permit adjacent buildings to be tied together by a common floor; the floors to be extended beyond the buildings to form uncovered porches; or narrow extensions of the floors may be formed to provide walks for connecting a number of adjacent buildings. Other ways of utilizing the floor structure will occur to those skilled in the art.

Moreover, while I have shown and described what is now thought to be the preferred embodiment

ments of the invention it is to be understood that the same is susceptible of other forms and expressions. Consequently, I do not limit myself to the precise structures shown and described hereinabove except as hereinafter claimed.

5 I claim:

A laminated sectional floor adapted to be mounted directly on the ground, comprising a rectangular central assembly of floor panels detachably connected together, at least two elongated rectangular assemblies of sill panels detachably connected to opposite sides of said floor panel assembly, said sill panels of said assemblies being interchangeable and reversible end-for-end, said sill panels and floor panels each comprising a top lamination of floor-providing material and a bottom lamination of resilient insulating material, sill boxes mounted atop each sill panel, the sill boxes of each sill panel assembly being in longitudinal alignment, said sill boxes each having upwardly converging side walls, each side wall being formed with means for connecting a wall panel thereto, each sill panel being formed with inner and outer rows of holes therethrough, said rows being on opposite sides of each sill box, the holes of said inner rows being diagonally downwardly directed in one direction, the holes of said outer rows being diagonally downwardly directed in an intersecting direction, and ground-engaging anchoring means for said floor extensible through said holes.

ALBERT DIETRICH.
